UNITED STATES PATENT OFFICE.

EUGÈNE SCHNEIDER, OF PARIS, FRANCE, ASSIGNOR TO SCHNEIDER & CIE, OF PARIS, FRANCE, A LIMITED JOINT-STOCK COMPANY OF FRANCE.

MACHINE FOR RESTRAIGHTENING GUN-CHARGE CASES.

1,313,560.

Specification of Letters Patent.

Patented Aug. 19, 1919.

Application filed February 14, 1918. Serial No. 217,199.

To all whom it may concern:

Be it known that I, EUGÈNE SCHNEIDER, a citizen of the French Republic, and a resident of 42 Rue d'Anjou, Paris, France, 5 have invented new and useful Improvements in Machines for Restraightening Gun-Charge Cases, which invention is fully set forth in the following specification.

Machines are employed at present for re-straightening the cases containing one element of a gun charge, after those cases have been fired one or more times. The majority of the machines hitherto known for this purpose comprise a matrix mandrel between the 15 walls of which the lips of the case are forced by the displacement of the mandrel or of the case by means of a screw-and-nut mechanism.

The present invention has for its object 20 to provide an improved machine for re-straightening gun charge cases, which comprises as in the known machines, a matrix mandrel between the walls of which the lips of the case are clamped for the purpose of 25 moving same.

The improved machine is characterized by the following features: The said mandrel carries in its prolongation a cylinder adapted to receive a liquid or a fluid under pressure, and between the two ends of which there is guided a rod carrying a diaphragm working in said cylinder. The portion of the rod that is guided in the end fixed to the mandrel, constitutes at its free end a support for the case that is to be re-straightened, while the portion of the rod guided in the opposite end of the said cylinder is pierced with longitudinal ducts for distributing the fluid under pressure alternately 30 upon one or the other of the sides of the diaphragm, and for discharging the fluid confined on the other side of the said diaphragm, and vice versa.

A practical constructional form of this invention is illustrated by way of example in the accompanying drawings in which:

Figure 1 is a longitudinal sectional elevation of the machine showing a case in place for being re-straightened.

Fig. 2 is a longitudinal section on the line II-II of Fig. 1, showing the parts of the machine in the position they occupy after this re-straightening operation.

Fig. 3 is a partial elevation corresponding 55 to Fig. 1.

Fig. 4 is a plan corresponding to Fig. 3.

Figs. 5 and 6 are cross sections on the lines V-V and VI-VI respectively of Fig. 1.

Fig. 7 is a partial section on a larger 60 scale on the line VII-VII of Fig. 2.

Figs. 8 and 9 are sections on the lines VIII-VIII and IX-IX respectively of Fig. 7.

The improved machine comprises in the 65 known manner, a mandrel A consisting of a cylinder open at one end and carrying on its other end a projecting boss B serving as a guide for a rod for centering or supporting the case D which is to be re-straightened. 70 The lips of the case are clamped, for the purpose of re-straightening, between the suitably shaped inner wall a of the end of the cylinder and the outer surface b of the boss B.

According to the present invention, a cylinder C is formed as a prolongation of the end of the matrix mandrel A-B. In the ends C¹, C² of this cylinder there is guided a rod E-F upon which is fixed a 80 diaphragm G held inside the said cylinder C. The portion E of the rod that is guided in the end C¹ that is common to the cylinder C and the mandrel A, forms with its head e, of known construction, a support for the 85 base of the case which is to be re-straightened. The portion F of the rod that projects beyond the other side of the diaphragm G and is guided in the end C² of the cylinder C, is pierced with two longitudinal ducts 90 f-f¹. The duct f communicates at one end through a duct g with the lower side of the diaphragm G. The duct f¹ communicates through a duct g¹ with the upper side of the said diaphragm. The lower ends of the 95 ducts f-f¹ open into the corresponding ports h-h¹ of a distributor H. The distributor H is connected by two pipes I and J to a pump K of known construction. The pipe I which serves for the admission of the 100 liquid or fluid under pressure compressed by the pump, can be placed alternately in communication either with the port and duct h-f or with the port and duct h¹-f¹, according as one or the other of the two needle 105 valves L, M is opened or closed. The discharge pipe J may be placed alternately in communication with the port and duct h-f or with the port and duct h¹-f¹ by means of branch passages j, j¹ according 110

as the needle valve N is opened and the needle valve O is closed, and vice versa.

In the example shown, the matrix mandrel A—B combined with the cylinder C, is assumed to be movable relatively to the diaphragm and rod E—G—F which is fixed upon a support P carrying the distributor H. To the support P are fixed two uprights Q, Q¹ which serve as guides for lugs A¹ 10 of the cylinder A. To the upper end of the upright Q there is hinged a plate R which can be raised into the position indicated in dot and dash lines in Fig. 1, for the purpose of inserting a case for re-straightening, or it can be turned down into the position shown in full lines in the same figure for the purpose of serving as a support for the barrel of the case during the re-straightening of the latter. The plate R 15 may be fixed in its turned down position by means of a bolting device located on the upright Q¹, shown more particularly in Figs. 3 and 4.

When the parts are in the position shown 20 in Fig. 1, and a case to be re-straightened has been placed in position upon the head of the rod E, the needle valves L M N and O are moved into the position indicated in Figs. 7, 8 and 9. The pump K having been 25 set going, the liquid under pressure is forced through the pipe I and the port and duct h¹—f¹ on to the upper side of the diaphragm G. The matrix mandrel A—B together with the cylinder C carried by it, is raised into 30 the position shown in Fig. 2. During the ascent of the cylinder C, the liquid confined between the end C² and the underside of the diaphragm G is forced by way of g—f—h—j and the pipe J back to the pump K. 35 When the mandrel has been kept in operation during the desired period, the needle valves are operated, namely L and O are 40 opened, and N and M are closed, whereby the liquid under pressure is forced under the diaphragm G, and the liquid confined 45 between the top of the diaphragm and the end C¹ of the cylinder C is discharged to the pump K. At the end of this stroke, the parts have resumed the positions shown in 50 Fig. 1, and after raising the plate R, the re-straightened case can be removed and a fresh case inserted for re-straightening.

What I claim is:—

1. In a machine for re-straightening gun

charge cases after having been fired, the 55 combination of a matrix-mandrel having an annular recess for receiving the open end of the case to be re-straightened, a cylinder for receiving fluid under pressure, constituting a coaxial prolongation of said 60 mandrel, a piston or diaphragm working in said cylinder, a rod carrying said piston or diaphragm, extending through both ends of said cylinder with a portion projecting beyond said mandrel, a support for the case 65 to be re-straightened, located on said projecting rod portion, and longitudinal ducts pierced in the other rod portion projecting beyond the opposite side of said diaphragm, 70 for distributing the fluid on to one side of said diaphragm and discharging the fluid confined on the other side of said diaphragm, and vice versa.

2. In a machine for re-straightening gun charge cases after having been fired, the 75 combination of a movable matrix-mandrel having an annular recess for receiving the open end of the case to be re-straightened, a movable cylinder for receiving fluid under pressure, constituting a co-axial prolongation of said mandrel, a fixed piston or diaphragm working in said cylinder, a fixed rod carrying said piston or diaphragm, 80 extending through both ends of said cylinder with a fixed portion projecting beyond 85 said mandrel, a support for the case to be re-straightened, located on said projecting rod portion, longitudinal ducts pierced in the other fixed rod portion projecting beyond the opposite side of said diaphragm, 90 for distributing the fluid on to one side of said diaphragm and discharging the fluid confined on the other side of said diaphragm, and vice versa, fixed supports projecting 95 beyond the open end of said mandrel, serving as guides for said mandrel and said cylinder, a plate hinged to one of said fixed supports, serving as an abutment for the case during the re-straightening operation, and a fastening for said plate during the 100 re-straightening operation.

In testimony whereof I have signed this specification.

EUGÈNE SCHNEIDER.
